H. SHOEMAKER,
INDUCTION COIL.
APPLICATION FILED SEPT. 1, 1904.

UNITED STATES PATENT OFFICE.

HARRY SHOEMAKER, OF JERSEY CITY, NEW JERSEY, ASSIGNOR TO INTERNATIONAL TELEGRAPH CONSTRUCTION COMPANY, OF NEW YORK, N. Y., A CORPORATION OF NEW YORK.

INDUCTION-COIL.

SPECIFICATION forming part of Letters Patent No. 783,802, dated February 28, 1905.

Application filed September 1, 1904. Serial No. 222,929.

To all whom it may concern:

Be it known that I, HARRY SHOEMAKER, a citizen of the United States, residing at Jersey City, in the county of Hudson and State of New Jersey, have invented a new and useful Induction-Coil, of which the following is a specification.

My invention relates to induction-coils or transformers, more especially, though not exclusively, those of the open magnetic-circuit type.

My invention comprises an induction-coil or transformer whose parts are so disposed and arranged that they are easily portable and easily assembled and connected for use.

My invention consists also of means for protecting the secondary winding against breakdown, more especially when such winding is either in conductive or inductive connection with a circuit traversed by high-frequency oscillations, such as employed in wireless telegraphy and the like.

For an illustration of one of the numerous forms which my invention may take reference is to be had to the accompanying drawings, in which—

Figure 1 is a vertical elevational view of the complete apparatus. Fig. 2 is a vertical sectional view of the core and primary winding. Fig. 3 is a top plan view of a group of secondary windings. Fig. 4 is a vertical sectional view of a group of secondary windings. Fig. 5 is a horizontal plan view of the separator. Fig. 6 is a simple diagrammatic view of the secondary winding, showing the heavily-insulated end sections.

Referring to Fig. 1, T is a tripod, whose three legs are shown at a, b, and c. Upon the tripod T rests a member consisting of the disk A, having the downwardly-extending ribs r. This member serves as a separator between the top of the tripod T and the sections S of the secondary winding. The tripod T and the separator A are both preferably constructed of wood or other insulating material.

Each section S of the secondary consists of a group of pancake sectional windings or coils, as s, consisting of numerous convolutions of

fine wire wound into flat coils, the convolutions and layers being insulated by wax or other suitable material. Each coil or section s is separated from its neighbor by thick waxed paper or other suitable material. The numerous coils or sections s are mounted upon and insulated from the tube t, made of mica, micaestos, micanite, or other suitable highly-insulating material. The coils s are confined between the ends e and covered by the casing f, the ends and casing being of a material similar to that of the tube t. This construction affords a portable section of a secondary which may be handled and shipped without difficulty and without danger to the windings. The several coils s are connected in series with each other, so that the electromotive forces generated in them are cumulative. As shown, two large sections S are provided and rest upon a member A. These sections are connected in series with each other, so that their electromotive forces are cumulative. The terminals of the entire secondary are at g and h. The pancake coil of the lower section S and whose end connects with the binding-post h and the end coil in the upper section S and whose terminal connects with the binding-post g are constructed differently from the remainder of the coils s. These end coils or sections are wound preferably of larger conductor very heavily insulated, so that the neighboring convolutions or layers shall be separated a much greater distance than separates the convolutions or layers of the other sections s, or these end sections may be wound of conductor of the same size as the conductor forming the other sections s; but the insulation must be great, so that the convolutions or layers shall be separated relatively greater distances. This for the following reason: Secondary windings used in connection with oscillatory circuits or any circuit in which relatively high-frequency oscillations are generated or exist when wound in the usual way—that is, the end sections of the secondary being wound in such manner that the convolutions or layers are relatively close to each other—are found

to break down and become inoperative after relatively short usage. This I have found to be due to the fact that the high-frequency oscillations pass to the secondary windings 5 and, as well-known to be the fact in connection with high-frequency oscillations, generate great differences of potential between neighboring convolutions, such convolutions forming an inductance, with the result that 10 the insulation between convolutions or layers is not great enough to prevent puncture of such insulation, and in consequence short-circuiting of neighboring convolutions or layers under the influence of these high potentials developed 15 by the oscillatory currents occurs even though the insulation is great enough to withstand the potential differences generated by the secondary windings themselves. The result is that after one short circuit has been thus formed another and another will occur, and this short-circuiting will eat its way from each end toward the middle of the secondary winding and in a short time render the secondary 20 incapable of supplying high-potential currents. To obviate this defect, I construct the end coils of the secondary of relatively fewer convolutions and insulate them very highly—in fact, so highly that the high potentials generated by the high-frequency oscillations can- 25 not puncture the insulation. However, the length of conductor or number of convolutions comprising these end sections and thus highly insulated is such that enough inductance is offered to the high-frequency oscillations to prevent these oscillations from reaching the inner sections of the secondary, which are wound and insulated in the usual manner. 30 In other words, these end sections operate simultaneously as choke-coils and as active 35 coils of the secondary winding, adding their electromotive forces to those of the other sections or coils. These highly-insulated end sections are shown diagrammatically in Fig. 6 at *k k*. The larger cross-sectioning shown 40 at *k* in Fig. 4 also represents this feature. 45

C represents the core, consisting of numerous fine iron wires confined within the fiber tubes *F*.

l is a rod extending longitudinally through 50 the core *C* and threaded at each end to receive the nuts *m m*. By screwing up these nuts *m m* the fiber heads *n n* are drawn tightly against the ends of the core *C*. The fiber tube *F* and the ends *n n* constitute an insulating-housing for the core, as well as mechanical means for holding it rigidly in position. Upon the fiber tube *F* and between the ends *n n* is wound the primary coil, consisting of a suitable number of layers of suitably-sized conductor. 55 Covering the primary winding *P* is another tube, *c*, consisting of mica, micabes- 60 tos, micanite, or other suitable highly-insulating material. This tube is confined between the fiber ends *p p*, which are clamped

in position by the nuts *q q*, which also engage 65 the rod *l*.

At *u v* are the terminals of the primary *P*, which are led out through the two fiber heads *p n*. This construction affords an easily-portable, mechanically-strong, and highly-insulated core and primary. The cylindrical openings through the tripod *T*, member *A*, and the sections *S S* of the secondary accommodate the combined core and primary, which is shown in position in Fig. 1. To support 70 the primary core in proper position, the fiber-bolts *w w* pass through the lower head *p* and engage in the tripod-head *T*, and the wooden disk *x*, resting upon the upper section *S*, supports the upper head *p* by means of the intervening wooden struts *y*. 75

The core and primary extend as much below the lower sections *S* of the secondary as they extend above the upper end of the upper section *S*, with the result that the secondary 80 winding is concentrated as near the central portion of the core *C* as possible. The magnetic leakage is thus minimized and the secondary voltage correspondingly increased. 85

It is apparent from the construction herein 90 described that the induction-coil or transformer may be dismembered easily and quickly into very few parts, each of which is mechanically strong, highly insulated, and easily portable.

What I claim is—

1. A transformer comprising a core and primary winding assembled as an independent member, and a secondary consisting of a plurality of independently-portable sections, each 100 section consisting of a plurality of coils.

2. A transformer comprising a core and primary winding assembled as an independent member, and a secondary consisting of a plurality of independently-portable sections, each 105 section consisting of a plurality of coils assembled in an envelop of insulating material.

3. In a transformer, a winding comprising a plurality of independently-portable sections, each section consisting of a plurality of coils 110 inclosed in an envelop of insulating material.

4. In a transformer, a winding comprising a plurality of independently-portable sections, each section consisting of a plurality of coils inclosed in an envelop of insulating material, 115 the coils connecting with the terminals of said winding being composed of conductor more highly insulated than the conductor of the other coils, and serving as means for excluding electrical oscillations.

5. In combination, a standard, a combined core and primary winding supported thereby, and a plurality of independently-portable sections of secondary winding supported by said standard and co-operating with said core and 125 primary winding.

6. A transformer comprising a core and primary winding assembled as a unitary mem-

ber, and a secondary comprising a plurality of independently-portable sections removably disposed about said primary.

7. In a transformer, a winding comprising a plurality of independently-portable sections, each section consisting of a plurality of coils inclosed in an envelop of insulating material, an end coil of a section consisting of conductor more highly insulated than the conductor of the other coils.

8. In a transformer, a winding consisting of a plurality of coils, a coil approximate a terminal of said winding consisting of conductor of greater cross-section and more highly insulated than the conductor of the other coils. 15
